United States Patent Office

Des. 206,556
Patented Dec. 27, 1966

206,556

CASE FOR PORTABLE PHONOGRAPH OR SIMILAR ARTICLE

Tobin Wolf, Bloomfield, and William J. Lawrence, Jr.,
Clifton, N.J., assignors, by direct and mesne assignments,
to The Singer Company, New York, N.Y., a corporation of New Jersey

Substituted for abandoned design application Ser. No.
79,041, Mar. 17, 1964. This application July 15, 1965,
Ser. No. 86,166

Term of patent 14 years

(Cl. D56—4)

FIG. 1.

FIG. 2.

FIG. 3.

FIG. 4.

FIGURE 1 is a perspective view of a case for a portable phonograph or similar article, showing our new design;

This application is a substitute for applicant's prior design application Serial No. D. 79,041, filed March 17, 1964 and now abandoned.

We claim:

The ornamental design for a case for a portable phonograph or similar article, substantially as shown and described.
